UNITED STATES PATENT OFFICE.

JOHN THOMPSON SMITH, OF NEW HAVEN, CONNECTICUT.

STEREOSCOPE CROSS-BAR.

SPECIFICATION forming part of Letters Patent No. 761,420, dated May 31, 1904.

Application filed October 23, 1902. Serial No. 128,517. (No model.)

To all whom it may concern:

Be it known that I, JOHN THOMPSON SMITH, a citizen of the United States of America, and a resident of the city and county of New Haven, 5 in the State of Connecticut, have invented certain new and useful Improvements in Stereoscope Cross-Bars, of which the following is a specification.

To secure the best results in using the stereoscope it is desirable that the views or pictures being examined should be held always in substantially the same position relatively to the axis of each lens. As ordinarily constructed the brace or receptacle wires at the ends of 15 the cross-bar are at a sufficient distance apart at each end to permit the ready insertion of the card or cards of views, and the cross-bar has a smooth upper surface. When the instrument is being used with only a single card 20 in position, the lower edge of the card is liable to slip back and forth between the brace-wires, and thereby change its position relatively to the focus of either lens, and the card will also be thrown at an inclination to the 25 axis of the lens, which will distort the picture to a greater or less extent. Where the wires are so short as to reach only a portion of the way to the top of the card, as is usually the case, this tipping becomes very objectionable 30 owing to the great distance to which the top of the card may move, and when the rear end of the shaft of the instrument or the end carrying the cross-bar is raised above the horizontal the top of the card will fall forward, 35 and thereby throw the picture into the shade.

I have discovered that by providing a stop or abutment for the lower edge of the card on the cross-bar the card will be held more nearly in a vertical position at all times and 40 will be prevented from tilting forward when the rear end of the shaft is raised above the horizontal. By forming the stop as a groove the bottom of the groove can be inclined downward toward the front wires, which will cause 45 the lower edge of the card to automatically slide down against the front wall of the groove and thereby be located and held in the best possible position for examination of the pictures. In addition to this, when two or more 50 cards are placed between the wires, as is most

desirable, and especially when there is an attendant for placing the cards in position, the upper edge of the rear card will be held at a slight distance above the top of the forward card, whereby the cards may be the more 55 readily separated for removing the forward card, which is done by placing the thumb or finger on top of the rear card and drawing it back a sufficient distance to admit of the insertion of the fingers between the two cards 60 to grasp and remove the forward card.

My invention therefore consists in providing a stereoscope with means in addition to the receptacles or wires for holding the pictures in a vertical position on the cross-bar, 65 as will be hereinafter more particularly set forth.

In the accompanying drawings, in which the same reference-numeral indicates the same part in each of the views in which it occurs, 70 Figure 1 is a broken perspective view of my stereoscope with a card in position and the top of the bar provided with a stop made according to my invention. Fig. 2 is a similar view of Fig. 1 with two cards in position. 75 Fig. 3 is an end view of my improved cross-bar; and Fig. 4 is a view similar to Fig. 1, but without a card, showing the top of the bar entirely exposed and provided with a longitudinal groove. 80

Referring more particularly to the drawings, the numeral 2 indicates a shaft partly cut away of an ordinary stereoscope, (not shown,) said shaft having the usual lenses at the forward end thereof and a cross-bar 3 85 loosely mounted, so as to be moved toward and from the other end of said shaft. Braces or wires are located at the respective ends of this cross-bar to form receptacles for the picture-card. Each of these wires, as is well-known, 90 is formed with an outwardly-bent loop 4 and two legs 5, which are placed far enough apart to permit the ready insertion and removal of the card or cards. (Herein marked 6.)

Intermediate the aforesaid receptacles I 95 form a stop preferably by means of a groove 7, which extends from one end of the bar 3 to the other. The bottom of this groove is inclined upwardly from the front to the rear, so that when a card is placed between the re- 100

ceptacles its lower edge will automatically move forward until it enters the deepest part of said groove and rests against its front wall 8, which is preferably formed at a short distance to the rear of the front legs of the receptacles. The rear edge of the groove 7 preferably comes to the surface of the top of the cross-bar 3 forward of the rear legs of the receptacles, as at 9. Instead of providing the top of the cross-bar with a groove having an inclined bottom the entire surface, as a substitute, can be inclined and the stop formed by this inclined surface, as will be understood. By constructing the cross-bar of a stereoscope 15 in this manner it is evident that when a card is placed between the receptacle-wires its lower edge will automatically slide down to the bottom of the inclined surface, where it will remain substantially stationary while being viewed irrespective of the movement or change of position of the instrument which is liable to occur while being held in the hand of the observer. By thus locating the stop intermediate the front and rear legs of the 20 receptacles the lower edge of the card will be held stationary and will thereby reduce the angle of inclination which the card may assume as the upper portion moves back and forth between the tops of the receptacles. In 25 addition to these advantages with a single card when two or more cards are being used the rear card will rest upon the rear or upper portion of the groove, which will cause its upper edge to project slightly above the top 30 of the forward card, as shown in Fig. 4, in which position it can be more readily engaged by the thumb or fingers and bent back a sufficient distance for the insertion of the fingers to engage with and remove the forward card. 35 As soon as the forward card has been removed the rear card will automatically move forward to take its place, and thereby give room for the insertion of another card. 40

Having described my invention, what I claim, and desire to secure by Letters Patent 45 of the United States, is—

1. In a stereoscope, a cross-bar provided with a groove in its upper surface of sufficient width for receiving a series of exhibit-cards and extending throughout the length of 50 the cross-bar, the front wall of said groove being arranged at an approximately vertical plane, and the bottom thereof inclining upwardly and rearwardly from the lowermost portion of said front wall to the upper surface 55 of the cross-bar and extending throughout the length of the groove, whereby the foremost card is maintained in abutment against said front wall by the cards arranged in the rear thereof. 60

2. In a stereoscope, a cross-bar provided with a continuous groove in its upper surface for receiving a series of exhibit-cards, the front wall of said groove being arranged at an approximately vertical plane, and the bottom thereof inclining upwardly and rearwardly from the lowermost portion of said front wall to the upper surface of the cross-bar, in combination with receptacle-wires at the ends of the cross-bar in line with said 70 groove. 65

3. A stereoscope cross-bar provided with a guideway for automatically moving the foremost of a series of cards forward, comprising a grooved top for the bar, said groove being continuous from end to end of the bar, and having an inclined bottom extending throughout its length, and of sufficient width for receiving a series of cards thereupon. 75

In testimony whereof I have signed my name 80 to this specification in the presence of two subscribing witnesses.

JOHN THOMPSON SMITH. [L. S.]
